WAGON BOLSTER JACK

Edward H. Schmidtke, Charles City, Iowa, assignor of one-fourth to Wesley G. Henke, Charles City, Iowa

Application April 9, 1945, Serial No. 587,369

7 Claims. (Cl. 298—11)

1.

This invention relates to a bolster jack for wagons and has for its object to facilitate the dumping of the contents of a wagon box.

Another object is to elevate the forward end of a wagon box and hold it in raised position while the contents is being discharged from the rear end and after the contents of the wagon box has been discharged to lower the front end of the box to normal horizontal position for refilling.

A further object is to facilitate the quick and rapid exchange of the jack for the ordinary wagon bolster which normally supports the forward end of the wagon box over the front axle.

The above and other objects may be attained by employing my invention which embodies among its features a jack comprising a bed adapted to be attached to the sand board or front axle of a wagon, an elevator adapted to ride between upstanding guides at opposite ends of the bed, said elevator being adapted to support the wagon box at its front end, and screw operated means between the bed and the elevator for lifting the elevator and lowering it with relation to the bed.

In the drawings:

Figure 1 is a transverse sectional view through a wagon looking toward the forward end and showing my improved wagon box jack in lowered position.

Figure 2 is a view similar to Figure 1 showing the wagon box in elevated position.

Figure 3 is a top plan view of a wagon box jack constructed in accordance with this invention and showing the elevator partly broken away to more clearly illustrate the details of construction.

Figure 4 is a side view of Figure 3 showing portions broken away to more clearly illustrate the details of construction.

Figure 5 is a transverse sectional view taken on the line 5—5 of Figure 4.

Figure 6 is a transverse sectional view taken on the line 6—6 of Figure 3, and

Figure 7 is a fragmentary end view of the jack illustrated in Figures 3 and 4 taken from the end to which the hand crank is attached.

Referring to the drawings in detail a wagon designated generally 10 includes the usual axle 11, supporting wheels 12 at opposite ends, which is connected by means of the usual fifth wheel 13 to the sand board 14 of the wagon. Under normal circumstances the front end of the wagon box 15 rests upon a bolster support by the sand board 14 and lies in a normally horizontal position on the wagon running gear.

2.

In the present invention I substitute for the usual wagon bolster my improved bolster jack designated generally 16 which will be described in detail as follows. The jack 16 is best illustrated in Figures 3 to 7, inclusive, and comprises a bed 17 formed of a channel section with the flanges turned upwardly as will be clearly seen upon reference to the drawings. Formed in the flanges of the channel section 17 and extending parallel to the web portion thereof are longitudinal slots 18 the purpose of which will hereinafter appear. Welded to the ends of the flanges are standards 20 the upper ends of which are pierced as at 21 to receive a stud 22 upon which a fulcrum roller 23, the purpose of which will be more fully described, is mounted. Welded or otherwise secured to the channel 17 at opposite ends thereof and to opposite side edges are vertically extending parallel guides 24 the upper ends of which are held in spaced parallel relation by spacers 25 surrounding tie bolts 26 (Figures 3 and 4). Tie plates 27 are welded to the inner faces of the flanges adjacent opposite ends and extend to the extreme ends of the web of the channel 17 to form reinforcements therefor and also help to sustain the guides 24 in vertical position.

Welded or otherwise secured to one pair of standards 20 near one end of the bed is a cross plate 28 formed with a central opening 29 in which one end of a screw shaft 30 is journaled. As shown, this screw shaft is mounted for rotation in a detachable plate 31 (Figure 5) which is supported upon the standards 20 at the opposite end of the bed and is provided with an aligning opening for the reception of the opposite end of the screw shaft. Pinned or otherwise attached to the end of the screw shaft which projects through the plate 31 is a socket 32 having a cross slot 33 for the reception of a cross pin carried by the crank handle 34 as illustrated in Figures 3, 4 and 5.

Mounted on the screw shaft 30 for longitudinal movement parallel to the axis of the bed 16 are nuts 35 which are provided with internal screw threads designed to mesh with the oppositely threaded portions of the shaft so that when the shaft is turned the nuts will move in opposite directions. As will be seen in Figure 6 each of the nuts 35 is provided with a transverse bore 36 for the reception of a transversely extending pivot pin 37 opposite ends of which ride in the slots 18 previously described. Mounted for swinging motion about each pivot pin 38 is a pair of arms 39 which lie upon the fulcrum sleeves 23 (Figure 4)

and carry at their outer ends transversely extending shafts 40 upon which lifting rollers 41 are rotatably mounted.

Resting upon the lifting rollers 41 and adapted to ride upwardly and downwardly between the guides 24 is an elevator designated generally 42 which comprises an inverted channel member 43 which is adapted to support the wagon box and carries adjacent opposite ends cross bars 44 which are of a length to extend beyond the width of the channel member 43 to serve as guides which ride against the outer edges of the guides 24 and prevent longitudinal displacement of the elevator with reference to the vertical guides 24.

Welded or otherwise secured to the guides 24 near their lower ends are angle bars 45 which serve as stops or rests for the wheels 41 when they are in lowered position.

In operation assuming that the truck body or box 15 is in lowered position and contains a load preparatory to dumping, when the time for discharging the contents arrives the crank handle 34 is inserted as illustrated in the drawings so that the cross pin carried thereby engages the cross slots 33 of the socket 32. Upon turning the crank handle the shaft 30 will be rotated thereby causing the nuts 35 to move away from one another and hence move the adjacent ends of the lifting bars 39 toward the outer ends of the bed 16. Due to the fact that the bars 39 rest upon the fulcrum rollers 23 it will be obvious that as their lower ends advance toward the fulcrum rollers the opposite ends will be lifted thus causing the lifting rollers 41 to exert a lifting action on the elevator 42 and hence cause the front end of the wagon box 15 to rise so as to discharge the contents through the rear end thereof. Having discharged the load the crank 34 is turned to the opposite direction so as to cause the nuts 35 to approach one another thus reversing the operation and lowering the wagon box to its normal horizontal position.

While in the foregoing there has been shown and described the preferred embodiment of this invention it is to be understood that minor changes in the details of construction, combination and arrangement of parts may be resorted to without departing from the spirit and scope of the invention as claimed.

What I claim is:

1. A jack adapted to be substituted for a wagon bolster comprising a bed adapted to be supported on the sand board or front axle of a wheeled vehicle, spaced parallel guides extending vertically from opposite ends of the bed, an elevator movable vertically between the guides, spaced parallel brackets extending upwardly from the bed near the guides, fulcrum rollers near the upper ends of the brackets, journal bearings carried by the brackets, a screw shaft journaled in said bearings to rotate about a longitudinal axis parallel with but spaced above the axis of the bed, nuts on the shaft adapted when the shaft is rotated in one direction to move toward opposite ends of the bed and when the shaft is rotated in the opposite direction to move toward the center of the bed, lever arms pivoted to the nuts and adapted to rest on the fulcrum rollers whereby when the nuts approach the fulcrum rollers the free ends of the lever arms will move upwardly adjacent the guides, and means to rotate the shaft.

2. A jack adapted to be substituted for a wagon bolster comprising a bed adapted to be supported on the sand board or front axle of a wheeled vehicle, spaced parallel guides extending ver-

tically from opposite ends of the bed, spaced parallel brackets extending upwardly from the bed near the guides, fulcrum rollers near the upper ends of the brackets, a screw shaft rotatably mounted between the brackets, nuts on the shaft adapted when the shaft is rotated in one direction to move toward opposite ends of the bed and when the shaft is rotated in the opposite direction to move toward the center of the bed, lever arms pivoted to the nuts and adapted to rest on the fulcrum rollers whereby when the nuts approach the fulcrum rollers the free ends of the lever arms will move upwardly adjacent the guides.

3. A jack adapted to be substituted for a wagon bolster comprising a bed adapted to be supported on the sand board or front axle of a wheeled vehicle, spaced parallel guides extending vertically from opposite ends of the bed, spaced parallel brackets extending upwardly from the bed near the guides, fulcrum rollers near the upper ends of the brackets, a screw shaft rotatably mounted between the brackets, nuts on the shaft adapted when the shaft is rotated in one direction to move toward opposite ends of the bed and when the shaft is rotated in the opposite direction to move toward the center of the bed, and lever arms pivoted to the nuts and adapted to rest on the fulcrum rollers whereby when the nuts approach the fulcrum rollers the free ends of the lever arms will move upwardly adjacent the guides, and rollers carried by the free ends of the lever arms.

4. A jack adapted to be substituted for a wagon bolster comprising a bed adapted to be supported on the sand board or front axle of a wheeled vehicle, spaced parallel guides extending vertically from opposite ends of the bed, an elevator movable vertically between the guides, spaced parallel brackets extending upwardly from the bed near the guides, fulcrum rollers on the brackets, a screw shaft rotatably mounted between the brackets, nuts on the shaft adapted when the shaft is rotated in one direction to move toward opposite ends of the bed and when the shaft is rotated in the opposite direction to move toward the center of the bed, lever arms pivoted to the nuts and adapted to rest on the fulcrum rollers whereby when the nuts approach the fulcrum rollers the free ends of the lever arms will move upwardly adjacent the guides, and rollers carried by the free ends of the lever arms.

5. A jack adapted to be substituted for a wagon bolster comprising a bed adapted to be supported on the sand board or front axle of a wheeled vehicle, spaced parallel guides extending vertically from opposite ends of the bed, an elevator movable vertically between the guides, cross bars near opposite ends of the elevator for engaging the outer edges of the guides to prevent endwise displacement of the shaft, spaced parallel brackets extending upwardly from the bed near the guides, fulcrum rollers near the upper ends of the brackets, a screw shaft rotatably mounted between the brackets, nuts on the shaft adapted when the shaft is rotated in one direction to move toward opposite ends of the bed and when the shaft is rotated in the opposite direction to move toward the center of the bed, lever arms pivoted to the nuts and adapted to rest on the fulcrum rollers whereby when the nuts approach the fulcrum rollers the free ends of the lever arms will move upwardly adjacent the guides, and rollers carried by the free ends of the lever arms.

6. A jack adapted to be substituted for a wagon bolster comprising a bed adapted to be supported

on the sand board or front axle of a wheeled vehicle, spaced parallel guides extending vertically from opposite ends of the bed, an elevator movable vertically between the guides, said elevator being adapted to support the forward end of a wagon body, spaced parallel brackets extending upwardly from the bed near the guides, fulcrum rollers near the upper ends of the brackets, lever arms resting on the fulcrum rollers and supporting the elevator at their outer ends and means to move the inner ends of the lever arms toward or away from each other whereby the elevator will be lowered or raised according to the direction of movement of the lever arms.

7. A jack adapted to be substituted for a wagon bolster comprising a bed adapted to be supported on the sand board or front axle of a wheeled vehicle, spaced parallel guides extending vertically from opposite ends of the bed, an elevator movable vertically between the guides, said elevator being adapted to support the forward end of a wagon body, spaced parallel flanges extending downwardly from opposite longitudinal sides of the elevator, cross bars near opposite ends of the elevator engaging the outer edges of the guides to prevent endwise displacement of the elevator, spaced parallel flanges extending upwardly from opposite sides of the bed and having longitudinal slots extending therethrough, spaced parallel brackets extending upwardly from the bed near the guides, fulcrum rollers near the upper ends of the brackets, a journal bearing fixed to one pair of brackets near one end of the

bed, a journal bearing removably attached to the opposite pair of brackets, a screw shaft journaled in said bearings to rotate about a longitudinal axis parallel with but spaced above the axis of the bed, nuts on the shaft adapted when the shaft is rotated in one direction to move toward opposite ends of the bed and when the shaft is rotated in the opposite direction to move toward the center of the bed, lever arms pivoted to the nuts and adapted to rest on the fulcrum rollers whereby when the nuts approach the fulcrum rollers the free ends of the lever arms will move upwardly adjacent the guides, rollers carried by the free ends of the lever arms and engaging the underside of the elevator whereby it may be moved vertically in the guides upon rotation of the shaft, and a hand crank detachably connected to the shaft for rotating it.
